UNITED STATES PATENT OFFICE.

ALBERT FISCHER, OF OBERHAUSEN, GERMANY.

REVERSING-VALVE FOR REGENERATIVE OR SIMILAR FURNACES.

SPECIFICATION forming part of Letters Patent No. 707,572, dated August 26, 1902.

Application filed August 8, 1901. Serial No. 71,370. (No model.)

To all whom it may concern:

Be it known that I, ALBERT FISCHER, a subject of the Emperor of Germany, residing at Muelheimerstrasse 87 to 89, Oberhausen, 5 Rhineland, Germany, have invented certain new and useful Improvements in Reversing-Valves for Regenerative or Similar Gas-Furnaces; and I do hereby declare the following to be a full, clear, and exact description of the 10 invention, such as will enable others skilled in the art to which it appertains to make and use the same.

The gas-valves of regenerative, Siemens, Martin, welding, melting, and similar furnaces, which are provided with a diagonally-arranged valve-disk, each time the inlet and outlet side is changed let fresh gas pass through and escape into the chimney-stack and further necessitate the arrangement of 15 special valves for regulating the quantity of gas flowing to and from the furnace. The gas-valve according to this invention obviates all waste when reversing the valve and enables the passage of the gas to be simultaneously regulated or entirely stopped up.

In the accompanying drawings, Figures 1 and 2 are sectional elevations of a reversing-valve constructed according to this invention, showing the valve in two positions. 20 Figs. 3 and 4 are a sectional elevation and a sectional plan, respectively, of another modified construction of valve; and Figs. 5 and 6 are similar views showing a further modification.

In the construction shown in Figs. 1 and 2 the gas-valve consists of two concentric cylinders *a* *b*, fitting closely together, open at both ends and provided with two openings *c* and *d*, situated opposite one another. The inner cylinder *b* is divided into two parts by 25 the partition *e*, which is inclined diagonally. To this partition *e* the rod *f* for reversing, or, rather, for turning, the cylinder *b* may be suitably attached. In order that this turning movement may be more easily performed, 30 the upper flange of the cylinder *b* runs on a ring of balls *h* in a ball-race provided in the upper flange *i* of the outer cylinder *a*. In order that the supply-gas and exhaust-gas 35 may not mix with one another through the interstices between the cylinders *a* and *b* the upper and lower edges of the inner cylinder *b* run in annular sand seals *k* provided in the

flanges of the outer cylinder *a*. To change the inlet and outlet side, the cylinder *b* is turned through one hundred and eighty degrees. 55 There is absolutely no connection between the two sides for a single instant during this turning motion, so that any loss of gas is a matter of impossibility. By gradually turning the inner cylinder the openings *c c* in the outer cylinder *a* may be reduced as required for the purpose of regulating or may be entirely closed.

Figs. 3 and 4 illustrate a further modification of gas-valve. In this case the valve-cheeks consist of two parts *m m*, made of fire-clay. The outer faces of these latter are flat and incased in four cast-iron plates *p p q q*, which are so fastened together that when the inner cylindrical faces of the parts *m m*, 70 which are spaced apart, wear away by the turning of the cylinder *b* the wear may be compensated for. For this purpose screw-bolts *r* are secured at the outer edges of the narrower plates *p p* and project through eyes 75 provided on the broader plates *q q*, and nuts *s* are screwed on the bolts outside the eyes. By screwing up these nuts *s* the fire-clay bodies *m m* may be followed up—that is to say, may be pressed up to the cylinder *b* to 80 form a good joint. The plates *p p* are provided with corresponding openings *t*. In this form of valve the upper sand seal *k* is rendered superfluous. The balls *h* run in a cast-iron race-ring *u*, which rests freely on the 85 fire-clay bodies *m*. These latter stand on a ring-shaped cast-iron foundation-plate *v* with the sand seal *k*.

A further modification is shown in Figs. 5 and 6. In this construction the ends *w* of 90 the gas-conduit butt up direct to the openings *d* in the cylinder *b* and are kept pressed up against the outer surface of this latter by means of spiral springs *x*. These springs are secured at each end to arms *y*, provided on 95 the conduit-noses *w*. The outer cylinder is formed of sections *z*, which are removably attached, by means of screws *l*, to the noses *w* and slightly spaced from the inner cylinder *b*. At the top and bottom, however, the section-plates *z* are bent in to fit up closely to the cylinder *b*. The plates *z* are divided at 100 2, so as to slide over one another. To further insure a good joint sand seals 3 may be

fixed over the cylinder-openings *d* onto the noses *w*. Here also the cylinder *b* runs in a sand seal *k*, provided in the foundation-plate *v*. At the top it runs on balls *h*, whose race 5 is secured on the top of the gas-chamber *4*, into which the gas-inlet mouths at *5*. This gas-chamber is fastened down onto a fixed 10 cast-iron plate *6*, with a downwardly-projecting flange which projects into the sand-seal groove in the top flange of the inner cylinder *b*. As the cylinder *b* under the influence of changing temperature expands or contracts, the noses *w* and divided plate-sections *z* can 15 follow the movement thus caused, the springs *x* assuring a good joint between *w* and *z* and *d*, so that no gas is lost when the cylinder *b* is turned. The butt-noses *w* are connected to the inlet and outlet conduits (not shown on the drawings) to slide.

20 What I claim, and desire to secure by Letters Patent, is—

1. A reversing-valve for regenerative and similar furnaces characterized by two cylinders *a* *b* arranged one to turn inside the 25 other open at both ends and provided with openings *c* *d* opposite one another to and from the furnace, the inner *b* of which cylinders being divided into two parts by an inclined

partition *e*, circular sand packings on the outer cylinder and lips on the inner cylinder 30 working in the said sand packings.

2. A reversing-valve for regenerative and similar furnaces, comprising a cylinder *b* with a diagonal partition, valve-cheeks *m* partly surrounding the cylinder and made in two 35 separate parts of fire-clay, and incasing plates *p* *q* holding the cheeks together in such a manner that they can be adjusted and pressed up against the cylinder *b* to form a good joint. 40

3. A reversing-valve for regenerative and similar furnaces, comprising an inner cylinder with openings and a diagonal partition, and an outer cylinder made of two divided plates *z* which are provided at the top and 45 bottom with bent-in flanges and with sliding noses *w*, in front of the openings *d* in the inner cylinder *b*, for the inlet and outlet conduits, springs *x* tending to draw the two parts of the outer cylinder together. 50

In testimony whereof I have affixed my signature in presence of two witnesses.

ALBERT FISCHER.
